UNITED STATES PATENT OFFICE.

JAMES N. C. GRAHAM, OF NEW YORK, N. Y.

CARD-MOUNT.

No. 884,086.

Specification of Letters Patent.

Patented April 7, 1908.

Application filed June 16, 1906. Serial No. 321,994.

To all whom it may concern:

Be it known that I, JAMES N. C. GRAHAM, a citizen of the United States, and a resident of borough of Brooklyn, Greater New York, 5 N. Y., have invented certain Improvements in Card-Mounts, of which the following is a specification.

My invention relates to cards or card mounts for passe-partout structures, and the 10 object of my invention is to provide a card mount designed and adapted to receive a picture or printed matter, with a removable calendar, picture, or other object to be shown through a transparent body covering 15 the face of the structure; the card being so constructed that when the passe-partout is made the removable calendar or picture carried thereby will be covered by and viewed through the transparent material, but at the 20 same time will be readily accessible for the purpose of removal or rearrangement.

My invention is fully shown in the accompanying drawing, in which:

Figure 1, is a perspective front view of my 25 improved card mount made into a passe-partout; Fig. 2, is a perspective rear view of the same; Fig. 3, is an enlarged vertical section, and Fig. 4, is a similar section of a portion of the structure, showing the manner in 30 which the calendar pages are removed or pictures inserted.

1 represents a card having a mount of the ordinary type for a picture 2, and an opening 3 which may be disposed in any suitable 35 part of the card. The card 1 is backed with a card 4 somewhat heavier, which is also provided with an opening 5 which should register with the opening 3 of the card 1. Hinged to the card 4 is a flap 6, which in this instance carries a calendar pad 7; the hinge 40 employed being preferably a piece of muslin 8 which may be entered between the two cards, in the manner shown in Figs. 3 and 4, and glued in place.

45 The opening 3 in the card 1 is slightly smaller than the opening 5 in the card 4, as clearly indicated in Fig. 3, so that only the central portion of such calendar sheets will be exposed to view through the opening 3, 50 the edges of such sheets being hidden by the marginal portion of said opening. The flap 6 carrying said pad is held in place by means of a suitable catch 9 carried by the card 4,

which may be readily moved out of the way when it is desired to raise said flap to tear 55 one of the calendar sheets therefrom. By this means when the card mount is combined with a plate of glass or other transparent material 10 and made into a passe-partout, in the manner indicated in the drawing, 60 the calendar is readily accessible for the removal of the expired sheets, or for the insertion of a new pad, without in any way injuring or marring the passe-partout.

65 I claim:

1. A picture and calendar card comprising a mount having an aperture therein, a backing for said mount, means for securing the mount and backing together, said backing having an aperture registering with the 70 aperture of the mount, a freely movable hinged flap carried by the backing for closing its aperture, a tear-off calendar pad carried by said flap and disposed in the aperture of the 75 backing and arranged to show through the aperture of the mount, and securing means carried by said backing for holding said flap and calendar in place.

2. A picture card mount having an aperture therein, a backing for said mount, 80 means for securing said backing and mount together, said backing having an aperture registering with the aperture of the mount, a hinged flap carried by said backing and serving to close the aperture in the same, a 85 calendar pad carried by said flap and disposed within the aperture of the backing and showing through the aperture of the mount, in combination with a plate of transparent material covering the face of said 90 structure, said plate serving to protect the picture card mount and the calendar carried thereby, and the means confining the edges of said mount and backing securing the 95 transparent plate to said structure.

3. A picture card mount having an aperture therein, a backing for said mount, said backing having an aperture registering with the aperture of the mount, a hinged flap for closing the aperture of the backing, a tear-off calendar pad carried by said flap and disposed in the aperture of the backing and arranged to show through the aperture in the mount, means for securing said flap in the closed position, in combination with a plate 100 of transparent material covering and pro-

95

105

tecting said picture card mount and the calendar carried thereby and through which said calendar may be viewed, and means for confining the edges of said mount and back-
5 ing and securing said plate of transparent material to the mount.

In testimony whereof, I have signed my

name to this specification, in the presence of two subscribing witnesses.

JAMES N. C. GRAHAM.
